Int. Cl. D7—01

U.S. Cl. D36—2

FIG. 1 is an elevational view of a bowl or the like, showing my new design it being understood that the bands of cut ornamentation continue about the entire periphery in the paths indicated;

FIG. 2 is a bottom view thereof;

FIG. 3 is a sectional view taken along line 3—3 of FIG. 1, the broken line representing a candle holding element;

FIG. 4 is a development of the design; and

FIG. 5 is a sectional view taken along line 5—5 of FIG. 1.

The dominant feature of my design resides in the portions shown in full lines.

This application is a division of pending United States design patent application Ser. No. D. 11,701, filed Apr. 30, 1968.

I claim:

The ornamental design for a bowl or the like, substantially as shown and described.
